UNITED STATES PATENT OFFICE

2,533,630

SAFETY MEANS FOR COTTON HARVESTERS

John D. Rust, Memphis, Tenn.

Original application April 18, 1944, Serial No. 531,632. Divided and this application May 12, 1947, Serial No. 747,356

4 Claims. (Cl. 56—11)

1

My invention relates to certain new and useful improvements in spindle type cotton picking machines in general, and in particular to machines of the character disclosed in Letters Patent No. 1,894,198, issued January 10, 1933, No. Re. 19,411, reissued January 1, 1935, No. 2,085,046, issued June 29, 1937, and No. 2,200,303, issued May 14, 1940.

The primary object of the present invention is to provide safety means for automatically protecting the machine against injury in cases of abnormal harvesting conditions, said means to include in combination with the doffing mechanism and the spindles as they proceed toward the doffer, a means for automatically stopping the machine in the event of any clogging of the delivery system.

Other objects will in part be obvious and in part will be pointed out hereinafter.

To the attainment of the aforesaid objects and ends the invention further resides in those novel details of construction, combination and arrangement of parts, all of which will be first described in the following detailed description, and then be pointed out in the appended claims, reference being had to the accompanying drawings, in which:

Fig. 1 is a top plan view of a cotton picking unit embodying my present invention, parts being broken away and other parts being shown in section.

Fig. 2 is a detail perspective view of the wall plate forming a part of a circuit closing device.

Fig. 3 is a schematic side elevation of a self-propelled machine embodying the invention.

In the drawings, like numerals of reference indicate like parts in all the figures, beginning with Fig. 1 the numeral 1 represents the main frame of the machine, 2 the driving shaft, and 3 the driven shaft of the spindle-carrying slat belt.

The shafts 2 and 3 carry the sprocket wheels 4 about which the chains 5 pass. The chains 5 carry the slats 6 in which the spindles 7 are rotatably mounted. All of the foregoing may be of the usual construction as these parts, per se, do not comprise a part of the present invention, nor does the front guard comb device 8 for the stalk guards 9 constitute a part of the present invention, the guard comb 8 being present to prevent cotton being drawn over the front end of the stalk guards 9 between the guards 9 and the chains and slats.

On the curved bar 10 of the inner frame 10, 11 of the machine is a bridge member 12 which forms, with the bar 10, a slot into which one end

2

of a floating bar 13 projects. The other end of the bar 13 is spring loaded as at 47. The bar 13 carries a stub shaft 14 on which is mounted a pair of connected pulleys 15 and 16. A belt 18 passes about the pulley 16 and about a pulley 17 on the shaft 2, while a belt 19 passes about the pulley 15 and a pulley 20 on the doffer shaft 25. The doffer saws 21 are carried in suitably spaced relation by the shaft 25 and the teeth 21^x of the saws project between stripper bars 22 secured to an upright support 23 fixed to the frame of the machine. The picking spindle 7 in their travel pass between the saws and the bars 22 in a manner similar to that disclosed in my Patent No. 2,200,303 aforesaid.

Referring now to the tiltable wall plate 27, a detail of which is shown in Fig. 2, a pin 26 is carried by and projects upwardly from the frame bottom cross bar 1^a to receive a tubular bearing 20 29 that is welded or otherwise suitably secured to the lower end of the wall plate 27. The plate 27 extends from adjacent the doffer to the throat 38 of the suction duct 39 and has a wing 30 that projects into that throat and a flange 31 that lies outside but along the throat vertically. The wing 30 and the flange 31 serve as stops for the plate. The plate 27 is bent back upon itself as at 28 for a purpose presently made clear. The upper edge of the plate 27 is notched as at 32 to 30 receive the hook end 36 of an arm 35 that is secured to the outer end of a spring arm 34. The arm 34 is fixed at its other end to a bracket 33 secured to the frame bar 1^b. The arm 34 is one element of a circuit closer, the other element of 35 which is an insulated fixed contact 37 suitably mounted on a frame bar 1^b.

In Fig. 3 is schematically shown a tractor whose frame 51 carries the usual power plant 50 having a magneto 49. The arrangement of Fig. 40 3 is like that shown in my Patent No. 2,073,653 aforesaid. In Figs. 1 and 3, M designates the cotton picking machine. The magneto 49 is connected by a wire 46 to contact 37, the return being via the frames of the machines.

In the event that vines, limbs, or anything obstructs the passage of the cotton through the suction pipe, then the cotton being stripped from the spindles would rapidly fill up the space between the stripper comb and the portion 28 of the movable wall 27. The spindles would crowd the cotton against the element 28 and cause the wall 27 to lean away from the spindles and close the circuit, thereby grounding the magneto and stopping the machine so as to avoid damage and 55 to enable it to be cleaned quickly. As the ac-

cumulated cotton forces wall 27 away from the spindles by the pressure of the cotton against the wall portion 28 the arm 25 will be pulled and the spring arm bent against contact 37 to close the circuit. By lifting the hook 36 and consequently releasing the wall 27, the wall may be lifted out of the machine, thereby giving room for access to the piled up cotton without the necessity of unbolting the parts.

This application is a division of my application Serial No. 531,632, filed April 18, 1944, now Patent No. 2,458,531.

From the foregoing description, taken in connection with the accompanying drawing, it is thought the construction, operation and advantages of my invention will be clear to those skilled in the art.

What I claim is:

1. In a cotton picking machine having a plurality of rotating cotton gathering spindles, means for removing the cotton from the spindles including a stripping comb: the improvement which includes a fixed circuit closing element; a yielding circuit closing element located adjacent the comb and constituting one wall of a cotton discharge passage, which yielding circuit closing element is operated by the pressure of an abnormal accumulation of cotton between the said one wall and the comb.

2. In a cotton picking machine wherein are provided sets of rotating cotton gathering spindles, a set of stripping bars between which the spindles are drawn to remove the cotton from the spindles, a rotary doffer which includes circularly arranged sets of teeth on a rotating body, the teeth projecting between the stripping bars and lying in planes above the spindles: the improvement which includes walls forming a passageway into which the doffer throws the cotton, said passageway having one of its walls spaced from the stripping bars to constitute therewith a throat, and a circuit closing means operable by the tilting of said last named wall under excess pressure of cotton against the outside of the wall, and an electric circuit including said circuit closing means.

3. In a cotton picking machine wherein are

provided sets of rotating cotton gathering spindles, a set of stripping bars between which the spindles are drawn to remove the cotton from the spindles, a rotary doffer which includes circularly arranged sets of teeth on a rotating body, the teeth projecting between the stripping bars and lying in planes above the spindles: the improvement which includes walls forming a passageway into which the doffer throws the cotton, said passageway having one of its walls spaced from the stripping bars to constitute therewith a throat, and a circuit closing means operable by the tilting of said last named wall under excess pressure of cotton against the outside of the wall, and an electric circuit including said circuit closing means, said wall having a stop to limit its tilting outwardly, said circuit closer including a springy contact arm connected to said wall for drawing the wall outwardly against said stop when the wall is free of the excessive pressure which would tend to tilt the wall inwardly.

4. In a cotton picking machine having a plurality of cotton gathering spindles and a stripping comb: the improvement which includes a fixed circuit closing element, walls forming a cotton discharge passage, one of said walls being yieldable and carrying a second circuit closing element, said yieldable wall being located adjacent the entrant end of said comb and being operable by the pressure of an excessive amount of cotton between the stripping comb and the adjacent portion of said yieldable wall, and an electric circuit containing said circuit closing elements.

JOHN D. RUST.
